FIG. 6.

INVENTOR
HUBERT SCHISKE

BY *O. Schiske*

his ATTORNEY

UNITED STATES PATENT OFFICE.

HUBERT SCHISKE, OF MUNICH, GERMANY.

CARBURETOR.

Application filed January 6, 1926, Serial No. 79,516, and in Germany October 17, 1925.

The invention relates to carburetors of the kind in which a float controls the fuel inlet valve by means of lever mechanism.

It is a common experience with such carburetors that difficulties arise when one fuel is substituted for another having a different specific gravity, because the change of buoyancy causes the liquid level to be changed, so that it is necessary to insert a new float, or change the length of the inlet valve stem, or make some other more or less difficult adjustment.

The object of this invention is to provide a carburetor with float-actuated mechanism which can in a more simple manner be adjusted for fuels of different specific gravities.

To this end means are provided for adjusting or regulating the clearance between the bottom of the tank or a given appropriate liquid level and the lever which is actuated by the float, so that when the specific gravity of the fuel is changed the float can assume the new normal position due to the changed buoyancy without thereby effecting the position of the valve. In combination with the adjusting device for this purpose, the valve seat may be made vertically adjustable, for the purpose of affording a wider range of adjustment.

Three examples of apparatus according to the invention are shown in the accompanying drawing, in which—

Figs. 1 and 2 are vertical sectional views of one form of the invention, with the lever arm which engages the float in different positions; Figs. 3 and 4 are views corresponding, respectively, with Figs. 1 and 2 of a modified form of the invention, and Figs. 5 and 6 are views corresponding, respectively, with Figs. 1 and 2 of a still further modified form of the invention.

Referring first to Figs. 1 and 2, the float *a*, when lifted, bears against one arm of a double armed lever *b*. The lever is mounted upon a pivot *c* supported in a bearing *c*¹⁰, from which pivot the lever can be withdrawn by hand. The other arm of the lever engages between collars *b*² on the valve stem *d*. The arm in contact with the float has an enlarged end portion *e* with two curved surfaces *f* and *g* at opposite sides of the lever, the curves being segments of circles of different radii. The curved part *f* forms on one side of the lever a projection which is substantially larger than the projection

formed on the opposite side by the curved part *g*. In Fig. 1 the curved surface *f* is shown in contact with the float *a*, but by slipping the lever off its pivot, inverting it and thus reversing the curved surfaces *f* and *g*, and then replacing the lever the curved surface *g* is placed in contact with the float, as shown in Fig. 2. This is done when the fuel is changed for a fuel of higher specific gravity, whose buoyancy will lift the float through the additional distance equal to the difference between the size of projections *f* and *g*. To allow of more precise adjustment for fuels of intermediate specific gravities the valve seat *h* may be made vertically adjustable. The valve seat *h* has a friction fit in the fuel inlet nipple *a*³ and by driving the seat up or down in the nipple the desired adjustment is obtained.

In the modification shown in Figs. 3 and 4 the stem *d*¹ of the valve passes through a central passage in the float *a*¹, but in other respects the mechanism is similar to that shown in Fig. 1, each of the levers *b*¹ being mounted on a pivot *c*¹ supported in a bearing *c*¹⁰, from which pivot the lever can be withdrawn for inverting it, so that either the curve *f*¹ or the curve *g*¹ of the enlarged part *e*¹ can be placed in contact with the float. The valve seat *h*¹ may be vertically adjustable in the manner above described.

In the modification shown in Figs. 5 and 6 a double armed lever *b*² engaging the valve stem *d*² is mounted on a pivot *c*² from which it can be withdrawn, for inverting it. The lever has an eye *i*², which engages a stud on the float *a*², but can be withdrawn from the said stud. The axis of this eye does not pass through the centre line of the lever, so that by inverting the lever from the position in which it is shown the eye is raised or reversed in position and can then, without affecting the position of the valve, be re-engaged with the stud, with the float raised to a higher level due to increased buoyancy of the fuel.

In all forms of the invention, the device includes a conventional form of float chamber *a*¹⁰ with a fuel inlet *a*³ and a fuel outlet *a*²⁰.

What I claim as my invention and desire to secure by Letters Patent of the United States is:—

1. In a carburetor the combination of a fuel container, a float in said container, a fuel inlet valve, a valve actuating lever hav-

- ing an arm in the path of the float, and having reversible means for regulating the clearance between the lever in its valve closing position and the bottom of the container 5 without altering the operative relation between the lever and the valve.
2. In a carburetor the combination of a fuel container, a float in said container, a fuel inlet valve, a valve actuating lever having an arm in the path of the float, said arm having surface portions located respectively at different distances from the axis of said arm, and a support affording a fulcrum for said lever, capable of supporting said lever in alternative positions imparted to said lever by rotating it about its axis.
3. In a carburetor the combination of a fuel container, a float in said container, a fuel inlet valve, a valve actuating lever having an arm in the path of the float, said arm having at opposite sides thereof two surface portions located respectively at different distances from the axis of the arm, and a pivot for said lever adapted to support said lever in two alternative positions in which either one or the other of said surface portions faces the float.

4. In a carburetor the combination of a fuel container, a float in said container, a fuel inlet valve, a valve actuating lever having an arm in the path of said float, said arm having means non-symmetrical in relation to its longitudinal axis for engaging the float, and a support affording a fulcrum, for said lever adapted to support said lever in different positions imparted to the lever by rotation thereof about said axis.

5. In a carburetor the combination of a fuel container, a float in said container, a fuel inlet valve, a valve actuating lever having an arm in the path of said float, and a support affording a fulcrum for said lever, adapted to support said lever in two alternative positions which can be imparted to said lever by rotation thereof about a longitudinal axis, that portion of the lever arm which contacts with the float being non-symmetrical with the axis of the lever arm.

6. The combination claimed in claim 1, together with a vertically adjustable seat for the valve.

In witness whereof I have signed this specification.

HUBERT SCHISKE.
